UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

PUSHER PLATE FOR SLICING MACHINES

Application filed July 12, 1929. Serial No. 377,844.

My invention relates to a slicing machine of the type wherein a circular knife is employed, herein shown as motor driven, and with which a work carriage is employed, 5 means being provided for guiding the carriage across the face and past the cutting edge of the knife. One object of the invention is to provide an improved pusher plate for use with the carriage. Another object is 10 the provision of such a plate which shall slide with maximum ease toward and away from the face of the knife. Another object is the provision of means for automatically resisting outward movement of the pusher 15 plate away from the knife beyond a predetermined point. Other objects will appear from time to time in the course of the specification and claims.

I illustrate my invention more or less 20 diagrammatically in the accompanying drawings, wherein—

Figure 1 is a front elevation;

Figure 2 is an end elevation with parts in section.

25 Figure 3 is a plan view; and

Figure 4 is a detail.

Like parts are indicated by like symbols throughout the specification and drawings.

A generally indicates a base or support for 30 a slicing machine and A¹ ground engaging members or pads.

Mounted on the base A is a circular knife B with its knife shaft B¹ and pulley B² associated therewith. B³ indicates a belt extending to any suitable power source, for example an electric motor, not herein shown. B⁴ indicates a guard plate positioned in front of the knife B and including an arcuate edge B⁵ penetrating the recess B⁶ in front of the 35 knife. B⁷ indicates a generally bell shaped guard portion the edge of which penetrates the recess B⁸ at the rear of the knife.

C generally indicates a supporting structure upon which is mounted the gauge plate 40 C¹.

D generally indicates a track, herein shown as of circular cross-section, which has associated with it a rectangular guide track D¹. D² generally indicates a work supporting carriage slidably mounted on the track 45

D and provided with flanges D³ downwardly depending about the track D¹. D⁴ indicates any suitable adjustable engaging members adapted to engage the track D¹ and to prevent rotation of the carriage D² around the track D. D⁵ indicates a work supporting member positioned on the carriage D². I illustrate it as pivoted as at D⁶ to the carriage and connected to the carriage by the adjusting links D⁷ controlled by the locking member D⁸. It will be understood, however, that the invention herein described and claimed may be applied to other forms of work support.

E generally indicates a handle which serves also as a guide pin for the pusher plate E¹. E² indicates a manual handle for the pusher plate which is connected with the pusher plate by the member E³ and is connected with the guide pin E by the member E⁴ and the sleeve or additional handle member E⁵. Note that the sleeve E⁵ is adapted for manual grasp. As shown in Figure 4 the sleeve E⁵ is of interior diameter greater than the normal exterior diameter of the pin E. It is provided at the ends with bearings E⁶ E⁷. The lower edge of the pusher plate, as shown in Figure 1, extends across the entire width of the member D⁵ but is out of contact therewith. In order to obtain a bearing contact at the edge of the pusher plate opposite from the sleeve E⁵ I provide any suitable bearing member generally indicated as E⁸, the lower edge of the pusher plate being downwardly extended as at E⁹. The upper face of the member D⁵ may be milled or grooved or otherwise treated as at E¹⁰, to form a bearing for engagement with the member E⁸ or, in case it is worn down or removed with the downward projection E¹¹. As shown in Figure 1 a cover B¹⁰ is illustrated over the upper arc of the knife. This cover projects outwardly sufficiently to interfere with the movement of the carriage in case the carriage extends upwardly above the lower edge of the cover. In order to permit the tilting of the member D⁵ I cut away the upper edge or corner of the pusher plate as shown at E¹².

It will be realized that whereas I have de- 50

scribed and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

10 The use and operation of my invention are as follows:

I find it desirable to employ a pusher plate on the carriage which may be controlled by the hand of the operator which also controls the reciprocation of the carriage. Hence I provide the guide pin E which, in conjunction with the guide sleeve E⁵, serves as a handle whereby the carriage D² may be reciprocated across the face of the knife. At the same time, and with the same hand, the operator may urge the pusher plate toward the work. The member E⁴ may assist, being engaged by a finger of the operator's hand, if desired, or being interposed between the operator's fingers. The supplemental handle E² may also be employed, at the election of the operator, the operator employing whichever of the two handles suits his need and the length of his arm. The pusher plate is mounted for smooth movement upon the pin E and in order to produce this smooth movement I employ a relatively long sleeve E⁵. When the operator is withdrawing the pusher plate from the work or the face of the knife, this movement is so smooth that he can flip it back practically by the curve of a finger. It would be extremely disadvantageous to permit the pusher plate to drop from the machine and this risk of its dropping increases with the ease of movement of the pusher plate. I therefore have employed separate bearings E⁶ spaced apart in the sleeve E⁵. If the operator flips the pusher plate back away from the work, it slides over easily until the end of the pin E clears the outer bearing E⁶. Then, as shown in Figure 4, the weight of the pusher plate causes the outer end of the sleeve E⁵ to drop and the result is a cramping action on the sleeve E⁵ which immediately stops the movement of the pusher plate. The operator can, by slightly lifting the pusher plate, straighten the alignment of the inner bearing E⁶ and remove the plate, but the possibility of its accidental removal is practically eliminated.

The pusher plate is effective at all adjustments of the pivoted member D⁵, being formed, as at E¹⁰ to permit its penetration beneath the covers B¹⁰ throughout the entire range of adjustment of the support D⁵.

The lower edge of the pusher plate cannot cramp or scratch the upper surface of the member D⁵, since it is spaced out of contact therewith. However, in order to provide a guide or support for the edge of the pusher

plate opposite the guiding sleeve E⁵ I provide the terminal bearing element E⁷ or the downwardly depending portion E⁸. Preferably I employ an anti-frictional member E⁷ but it may be dispensed with and, if it wears down, the portion E⁸ takes its place with the relatively small increase in friction. A bearing may be formed or ground as at E⁹ on the edge of the member D⁵.

Note that the handle or pin E, which also serves as guide for the pusher plate, stops short of the cutting edge at the extremity of the cutting excursion, in such fashion that as long as the operator has hold of the handle he cannot cut himself. Referring for example to the dotted line shown in Figure 1, note that the handle E stops just short of the knife B. If the operator has his hand about the pin or handle E he cannot bring his hand into contact with the cutting edge of the knife. Note that the guard E²⁰ masks the cutting edge and is interposed between the end of the handle and the cutting edge when the device is in the dotted line position. The relation of parts shown in dotted line in Figure 1 will be understood as diagrammatic and it may be desirable, especially if the guard E²⁰ is omitted, to have the handle E positioned even more remotely from the cutting edge, at the end of the cutting stroke.

I claim:

1. In association with a slicing machine including a rotary knife and means for rotating it, and a work support movable across the face of the knife, a pusher plate associated with said work support, means for guiding it and supporting it for ready movement toward and away from the cutting plane of the knife, including a guide pin, a sleeve adapted to slide on said guide pin, bearings at the opposite ends of said sleeve adapted closely to engage said guide pin, the intermediate portion of the sleeve being spaced away from the guide pin, the guide pin being adapted to permit one of said bearings to slide beyond the end thereof, and thereby cramp the other bearing upon the pin.

2. In association with a slicing machine including a rotary knife and means for rotating it, and a work support movable across the face of the knife, a pusher plate associated with said work support, means for guiding it and supporting it for ready movement toward and away from the cutting plane of the knife, including a guide pin, a sleeve slidable along said guide pin and means for cramping said sleeve on said guide pin when the pusher plate has receded a predetermined distance from the cutting plane.

3. In association with a slicing machine including a rotary knife and means for rotating it, and a work support movable across the face of the knife, a pusher plate associated with said work support, means for guiding it and supporting it for ready movement to-

ward and away from the cutting plane of the knife, including a guiding element mounted on said work support, the pusher plate being freely movable therealong within a predetermined range of movement and means 5 for cramping said pusher plate on said guiding element when the pusher plate passes beyond said range.

4. In association with a slicing machine including a rotary knife and means for rotating it, and a work support movable across the face of the knife, a pusher plate associated with said work support, means for guiding it and supporting it for ready movement toward 10 and away from the cutting plane of the knife, including a guiding element mounted on said work support, the pusher plate being freely movable therealong within a predetermined range of movement and means effective for 15 increasing the difficulty of movement of said pusher plate along said guiding element when the pusher plate passes beyond said range.

Signed at Indianapolis, county of Marion and State of Indiana, this 20th day of June, 25 1929.

WILLIAM J. CAMPBELL.
